UNITED STATES PATENT OFFICE.

EDWARD B. McCONNELL, OF NEWARK, NEW JERSEY.

GRATE-BAR AND SUPPORT THEREFOR.

1,382,998.

Specification of Letters Patent. Patented June 28, 1921.

Application filed March 13, 1920. Serial No. 365,476.

To all whom it may concern:

Be it known that I, EDWARD B. McCONNELL, a citizen of the United States, and a resident of Newark, in the county of Essex 5 and State of New Jersey, have invented a new and Improved Grate-Bar and Support Therefor, of which the following is a full, clear, and exact description.

This invention relates to improvements 10 in grate bars and supports therefor, an object of the invention being to provide a grate bar having high and low trunnions at both ends, and provide supports for the grate bar so that the latter may be supported upon 15 either its high or low trunnion.

Heretofore, in the art, it has been the common practice to provide grate bars alternately arranged, one series of bars having high trunnions and the other series of bars 20 low trunnions so that when the bars are oscillated to shake the grate, the adjacent bars have their pivotal supports at different elevations so as to swing the grate bars in different arcs. I provide grate bars having both high and low trunnions at both ends 25 and provide suitable mounting which will enable the bars to be supported either on the high or low trunnions so that while all the bars are alike, they are perfectly interchangeable, and when a bar is broken or injured and needs replacement, a single type 30 of bar will answer all purposes and not require specially constructed bars for special parts of the grate.

With these and other objects in view the invention consists in certain novel features of construction, and combinations and arrangements of parts as will be more fully hereinafter described and pointed out in the 40 claims.

In the accompanying drawings—

Figure 1 is a view in end elevation of a set of grate bars showing the supporting frame in section;

Fig. 2 is a view in section on the line 2—2 of Fig. 1;

Fig. 3 is a view in section on the line 3—3 of Fig. 1; and

Fig. 4 is a view in side elevation of the 50 center carrying bar.

1 represents the frame of the grate having a center carrying bar 2 and end carrying bars 3. My improved grate bars designated by the reference numeral 4 are provided at both ends with high and low trun-

nions 5 and 6. The high trunnions 5 project beyond the low trunnions 6.

The center bar 2 is provided with alternately arranged high and low bearings 7 and 8 and below the high bearings integral 60 flanges 9 are formed and under these flanges 9, lugs 10 on the ends of the grate bars are adapted to swing to prevent vertical displacement of the bar.

The end or side supporting bars 3 are also 65 made with alternate high and low bearings 11 and 12. Below the high bearings 11 curved flanges 13 are provided to receive the lugs 10 on the ends of the grate bar and above the low bearings 12 the frame bars 3 70 are provided with curved slots 14 to accommodate the high trunnions 5 of the grate bar.

The grate bars are made with depending 75 crank arms 15 and connected by links 17 so that when these links are moved longitudinally, they will cause an oscillating movement to be imparted to the grate bars, it being understood that all of the bars supported on their low trunnions will have a 80 loose connection with the link to compensate for the different elevations of the bearings.

It will be noted that with my improved 85 construction the grate bars are readily interchangeable and can be supported either upon their high or low trunnions, and hence in the making of the grate I construct all grate bars alike and yet secure the desired results of supporting the adjacent grate bars on high and low trunnions respectively 90 so as to give the desired difference in oscillation to the bars in use.

Various slight changes might be made in 95 the general form and arrangement of parts described without departing from the invention, and hence I do not limit myself to the precise details set forth, but consider myself at liberty to make such changes and alterations as fairly fall within the spirit and scope of the appended claims.

I claim:

1. In a grate, a series of identical grate bars having high and low trunnions, and means for selectively supporting said bars on either their high or low trunnions. 105
2. The combination with a supporting frame having adjacent high and low bearings, and a series of grate bars, all of said grate bars having high and low trunnions at both ends, certain of said bars supported on 110

their high trunnions in the high bearings of the frame and the bars adjacent thereto supported on their low trunnions in the low bearings of the frame.

5 3. The combination with a supporting frame having adjacent high and low bearings, a series of grate bars, all of said grate bars having high and low trunnions at both ends, certain of said bars supported on their 10 high trunnions in the high bearings of the frame and the bars adjacent thereto supported on their low trunnions in the low bearings of the frame, curved flanges on the frames below the high bearings, and lugs 15 on the ends of the bars movable under said flanges.

4. The combination with a supporting frame having adjacent high and low bearings, a series of grate bars, all of said grate bars having high and low trunnions at both 20 ends, certain of said bars supported on their high trunnions in the high bearings of the frame and the bars adjacent thereto supported on their low trunnions in the low bearings of the frame, curved flanges on the frames 25 below the high bearings, lugs on the ends of the bars movable under said flanges, and said frame having curved slots above the low bearings receiving the high trunnions of the grate bars supported in the low bearings. 30

EDWARD B. McCONNELL.
